UNITED STATES PATENT OFFICE.

HARMON O. NELSON, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

CLEARER-MOUNTING FOR ROVING-FRAMES.

1,149,209.

Specification of Letters Patent. Patented Aug. 10, 1915.

Application filed July 30, 1913. Serial No. 781,918.

To all whom it may concern:

Be it known that I, HARMON O. NELSON, a citizen of the United States, residing at Whitinsville, in the county of Worcester and State of Massachusetts, have invented 5 the following-described Improvements in Clearer-Mountings for Roving-Frames.

The invention is an improved clearer cover construction for roving and like machines, its particular features comprising 10 means whereby the hinged support for the cover may be changed readily to accommodate close or wide settings of the draft rolls, and whereby the cover is interlocked with 15 its support in either or both positions, being readily removable from the stand by raising it to an upright position.

In the accompanying drawings: Figure 1 is a section of so much of an ordinary roving 20 frame roll stand and its appurtenances as will suffice to illustrate the mode of application of this invention thereto. The figure also shows one embodiment of the invention applied to such stand. Fig. 2 is a rear elevation 25 of the parts shown in Fig. 1, with one hinge in section on line II-II of Fig. 1. Fig. 3 is a detail of the hinge construction with the cover set for wide adjustments of the rolls; and Fig. 4 is a similar detail for 30 close adjustments of the rolls.

The drawings illustrate a roll stand 1, with a forward fixed journal seat 2, a middle seat 3, and a back seat 4, the latter two being adjustable on the stand toward and 35 from each other. The pillow of the rear-most journal seat 4, carries a back rod 5 to support the cap bar, which latter is comprised of a finger 6, a rod 7 adjustably set 40 screwed therein, and two top roll guides 8 and 9 adjustably set screwed to the rod. These two guides support the front and middle top rolls, while the back top roll is held 45 in place in a channel formed between the two vertical walls 10 and 11 of the cap bar finger 6. It will be understood, of course, that the cap bar is adapted to support the ends or gudgeons of two adjacent sets of top rolls, being therefore symmetrically formed, as usual, with channels for the roll 50 gudgeons on either side and with the rod 7 disposed centrally between the channels and centrally of the cap bar finger 6 by which it is supported. The cover 12 is hinged to

the cap bar finger and contains within it the clearer proper, which is comprised in the 55 present case of a block or frame 13, to the under side of which a belt or loop 14 of flannel or like material, is fastened in the manner shown. The block or frame 13 is 60 loosely supported in the cover by means of a pin and slot connection 15, so that when the latter is in working position, the flannel will have a suitable bearing upon all of the top rolls.

In Fig. 1 the roll journals and guides are 65 set at their widest separation and the cover is in proper relation to the rolls for such setting. If, however, the rolls are now to be set close together, it will be evident that the forward adjustment of the cap bar finger 70 75 will advance the cover and its clearer member too far forward to retain a proper bearing on the top rolls,—a condition which is commonly compensated by providing a different set of clearer covers for use when 80 the rolls are close set. The expense and inconvenience of the double set of covers is eliminated according to the present invention by providing the cover with plural 85 hinging provisions upon the cap bar and at 90 different distances from the bearings of the back rolls, which will provide one or more pivotal axes on which the cover may be hinged. Thus I provide on the cover a hinge member or arm 16, and on the cap 95 bar two hinge members 17 and 18, each adapted to coact with the member 16 when engaged therewith. The member 18 is rearward of the member 17, so that when the rolls are set close together, the cover may be 100 hinged to this member and thereby supported in proper relation to the top rolls.

The cap bar hinge members which are stationary hinge members, may consist of two projections or studs projecting laterally 105 from the shank of the cap bar finger, and the arm 16, which constitutes in the present case the hinging or movable hinge member, may consist of a hub portion 19 with a central bore constituting a pivot hole to receive either stud, and with an entrance slot or channel 20, through which the stud is passed when the members of the hinge are assembled or separated. This slot 20 is curved and so arranged with reference to adjacent 110 parts that when the cover is down, or in its

normal working position, an interlocking engagement will be formed between the engaging hinge members, which will prevent removal of the cover accidentally or otherwise, except when turned to an upright position. Thus it will be seen from Fig. 3 that the wall 11 of the cap bar finger will prevent withdrawal of the hub from the pivot stud 17, when the cover is applied to the widely separated rolls, and from Fig. 4, that the part or lug 21 will prevent such withdrawal when the cover is hinged to the stud 18, in position to accommodate the close set rolls. In both cases the swinging of the cover to an upright position, as indicated by the dotted lines, will turn the entrance slot to such position as will permit the hub to be withdrawn upwardly from engagement with the stud. The lug 21 may serve also the additional function of a stop or abutment to limit the opening movement of the cover and against which the shoulder 22 may rest while the cover remains in an upright position. A similar lug 23 is provided solely as an abutment stop to engage the said shoulder when the cover is hinged to the stud 18.

It will be observed in Fig. 2 that the pivot hole in the arm 16 and the entrance slot 20 thereof are formed only in one side of the hinge member but it will of course be understood that such hole and slot may extend entirely through the hinge member if desired. It will also be understood that each cover is provided with two arms, such as 16, one for engaging the pivot studs of one cap bar and the other for engaging the corresponding studs of another cap bar, although only one of such arms is shown in the accompanying drawings. It will be evident also to those skilled in this art that the precise disposition of the arms and their mode of connection with the cover or with the clearer, can be varied within wide limits, according to the design and circumstances of each particular case.

I claim:

1. In a roving or like machine, a roll-stand having adjustable roll-bearings and a cap-bar, in combination with a clearer cover for the rolls supported by the cap-bar, such cover being hinged to its support and the hinge provisions comprising front and rear hinge members, whereby the cover may be

hinged optionally on either of two hinge axes.

2. In a roving or like machine, a roll-stand and clearer-cover, and separable hinge members pivotally connecting the cover with the stand and comprising two stationary members and a hinging member, the latter interlocking in engagement with its stationary member to prevent separation when the clearer cover is in operation and being removable when the cover is moved upright.

3. In a roving or like machine, a roll-stand and clearer cover, separable hinge members pivotally connecting the cover with the stand and comprising parts adapted to provide a front or a rear hinge axis for said cover, the hinging hinge member being adapted to interlock in engagement with its stationary hinge member to prevent separation of the hinge when the cover is in use.

4. In a roving or like machine, the combination of a roll-stand and cap-bar adapted to support drafting rolls and accommodate different adjustments thereof, a clearer cover having a hinge-member thereon, and two stationary hinge members with either of which said cover member may be engaged.

5. In a roving or like machine, a roll-stand and cap-bar having adjustable roll supporting means, a clearer cover having a hinge member, two stationary hinge members with which the cover member may be engaged and a hinge abutment for each stationary member.

6. In a roving or like machine, a roll-stand, a cap-bar thereon and front and rear hinge members on the cap-bar, in combination with a clearer cover hingeable to either of said members.

7. In a roving or like machine, a roll-stand, front and rear stationary hinge members thereon, a clearer cover having a hinge member adapted for pivotal connection with either of said stationary members, and adapted to interlock in engagement therewith on movement of the cover to normal position.

In testimony whereof, I have signed this specification in the presence of two witnesses.

HARMON O. NELSON.
